(57)

CLAIM

The ornamental design for a cleaning utensil, as shown and described.

DESCRIPTION

FIG. 1 is a perspective view for a cleaning utensil showing my new design;

FIG. 2 is a top view thereof;

FIG. 3 is a left side view thereof, the right side being a mirror image;

FIG. 4 is a front view thereof;

FIG. 5 is a bottom view thereof;

FIG. 6 is a rear view thereof; and,

FIG. 7 is a second perspective view thereof.

The broken lines in the drawings illustrate portions of the utensil design components which form no part of the claimed design.
